UNITED STATES PATENT OFFICE.

ALBERT G. ELVIN, OF EAST ORANGE, NEW JERSEY.

FLUID-PRESSURE MOTOR.

1,030,063.

Specification of Letters Patent. Patented June 18, 1912.

Application filed March 10, 1910. Serial No. 548,358.

To all whom it may concern:

Be it known that I, ALBERT G. ELVIN, of East Orange, in the county of Essex and State of New Jersey, have invented a certain new and useful Improvement in Fluid-Pressure Motors for Fire-Box Doors or other Reciprocating Members, of which improvement the following is a specification.

My present invention relates to pneumatic door operating mechanism of the general class or type of that set forth in an application for Letters Patent filed by me February 5, 1907, Ser. No. 355,877, and its object is to provide an appliance of such type which shall attain the advantages of that of said application, and embody the further advantages of effecting both the opening and closure of the door by fluid pressure, of cushioning the movements of the door in both directions, and of the capacity of ready disconnection of the pneumatic operating mechanism whenever it may become necessary or desirable to manually operate the door.

25 The improvement claimed is hereinafter fully set forth.

In the accompanying drawings: Figure 1 is a front view of a firebox door operating appliance illustrating an application of my invention, with the operating cylinder thereof in longitudinal central section; Fig. 2, a side view, in elevation, of the removable door of the gear casing; Fig. 3, a view, partly in plan and partly in horizontal central section, of the operating cylinder; Fig. 4, a plan view, on an enlarged scale, of the left hand portion of the operating cylinder; Fig. 5, a vertical transverse section through the operating cylinder and valves, on the line *a a* of Fig. 4; Fig. 6, a similar section through the inclosure of the operating valve and exhaust regulating valve, on the line *b b* of Fig. 4; Fig. 7, a similar section through the upper portion of the operating cylinder, on the line *c c* of Fig. 4; and Fig. 8, a similar section through the gear case, on the line *d d* of Fig. 3.

My invention is herein exemplified in connection with a fire door appliance comprehending two door leaves or reciprocating members or sections, 9, 9^a, which are fitted to slide horizontally toward and from each other in guides, 3, on a door frame, and to cover and uncover, as the case may be, a firing opening in a firebox or furnace to which the frame is connected. The door

sections are moved from and toward each other, to open and close, respectively, the opening, by means of levers, 12, 12^a, pivoted by pins or bolts, 13, to a gear casing 60 hereinafter described, the lower and longer arms of said levers being coupled to the door sections. Intermeshing segment gears, 17, 17^a, are formed on the levers concentric with their pivots, 13, and by the oscillation 65 of said segment gears about their axes, the door sections will be moved from or toward each other, as the case may be. A hand lever, 18, is pivoted to the bottom guides of the door frame, and is provided with a 70 longitudinal slot, 18^a, engaging a pin, 18^b, fixed to the door section, 9, for the purpose of operating the door sections manually, when desired.

In the practice of my invention, as applied in connection with a door mechanism of the type above described, a fluid pressure cylinder, 25, is bolted to the top of the door frame, 3, and is closed, at one of its ends, in this case the left hand end, by a head, 26. 75 The cylinder, 25, is formed integral with, or fixed to, an open bottomed gear casing, 25^a, into which the segment gears, 17, 17^a, project, and through which it is connected to the door. The end of the cylinder opposite that to which the head, 26, is secured, 80 is open to the gear casing.

A piston, 28, is fitted in the cylinder, 25, and is formed integral with, or fixed to, a piston rod, 28^a, which is made of such diameter as to cause the area of the piston 85 effective for pressure to be substantially less on the piston rod side than on the opposite side, the former being, say, one half the latter, thus constituting the piston a differential one. The bore of the cylinder, 25, at, and for some distance from, its open end, 90 is in correspondence with the diameter of the piston rod, and the latter is, in this instance, shown as formed in two sections, 100 which are connected by a bolt, 28^b. The piston is fitted with packing rings, 29, and the piston rod with packing rings, 29^a. The end of the piston rod which projects through the open end of the cylinder, is 105 coupled, by a pin, 19^a, to an arm, 19, on the segment gear, 17, the pin passing through a longitudinal slot in the arm, so as to admit of the vibration of the latter about the axis of the segment gear. An extension, 28^c, is 110 formed on the outer end of the piston rod to prevent the pin from rolling down into

the gear casing when it is detached from the arm and temporarily stowed at the side of the extension. Movement to the right or to the left, as desired, is imparted to the piston by fluid pressure, as hereinafter described, and it will be seen that such movement will, through the segment gears and their connections, move the door sections apart, or bring them together, as the case may be.

The supply and exhaust of motive fluid to and from the opposite sides of the piston, 28, to effect the opening and closing movements of the door sections, are effected by the following means. A valve chamber 34, which is closed, at its top, by a removable plug, 34^a, is formed on one side of the operating cylinder, 25, said chamber communicating, at its bottom, with a cylindrical bore which extends through the wall of the cylinder and has a valve seat at its top for the reception of a door opening supply and exhaust valve, 33, which seats downwardly and is fixed upon a cylindrical stem, 35, fitting truly in the cylindrical bore and extending for a short distance below the lower end thereof. Another valve chamber, 54, which is closed at its top by a removable plug, 54^a, is formed in the metal of the cylinder, adjacent to the chamber, 34, and substantially in the vertical axial plane of the cylinder, said chamber communicating with the chamber, 34, by a port or passage, 43. A valve seat is formed in the bottom of the valve chamber, 54, for the reception of a door closing supply valve, 53, which seats downwardly and is fixed upon a cylindrical stem, 55, fitting truly in a cylindrical bore extending from the valve chamber, 54, into the bore of the cylinder, 25. The stem, 55, is recessed or reduced in diameter immediately below the valve, 53, and a port or passage, 53^a, extends through the stem, from the recessed portion, nearly to its lower end, and is continuously open, through lateral branches, to the bore of the cylinder around the piston rod, 28^a. The supply pipe, 31, communicates, through a port or passage 31^b, with the port, 43, which connects the pressure chambers, 34 and 54, and with a lubricating cup, 44, from which oil is supplied to the valves and to the cylinder, 25. A port or passage, 45, leads from the left hand end of the cylinder to a lateral branch port, 45^a, which opens into the bore in which the stem, 35, of the valve, 33, is fitted. The stem, 35, is recessed or reduced in diameter below the valve, and the port, 45^a, is continuously open to the space in the bore surrounding the recessed portion of the stem. An exhaust port, 48, leads from the bore to the atmosphere, said exhaust port being so located that when the valve, 33, is seated, it will be uncovered by the recessed portion of the stem, and will therefore be in communica-

cation with the ports, 45 and 45^a. When, however, the valve, 33, is unseated, the port, 48, will be closed by the portion of the stem of full diameter below it. The area available for discharge of fluid through the exhaust port, 48, may be varied, as desired, by a regulating valve, 51, formed on the end of an adjusting screw, 52 engaging a thread in the metal of the cylinder.

A shoe, 28^c, is fitted on the upper side of the piston rod, 28^a, in position to abut against the lower end of the stem, 55, of the valve, 53, said shoe being recessed at and adjacent to its end nearer the valve stem and upwardly inclined from its recessed portion, 75 which is not in contact with the valve stem, to its portion of full thickness. When, in the traverse of the piston rod to the right, the inclined portion of the shoe strikes the valve stem, it thereby unseats the valve, 53, 85 and holds it unseated during the remainder of its traverse to the right. When, in the traverse of the piston rod to the left, the recessed portion of the shoe comes below the valve stem, the latter is thereby freed from 90 contact with the shoe, and the valve, 53, is seated by the fluid pressure above it.

A rod, 39, having a head, 36, which is in contact with the lower end of the stem, 35, of the valve, 33, is fitted to slide vertically in 95 a guide, 37, on the door frame, and is coupled, at its lower end, to a double armed treadle lever, 41, pivoted to the door frame and carrying a treadle, 42, which normally stands at a level slightly above that of the 100 deck or firing floor of the firebox. By downward pressure of his foot on the treadle, 42, the fireman can, through the lever, 41, and rod, 39, unseat the valve, 33, and upon the release of such pressure, the valve will be seated by the pressure from the supply pipe acting upon it in its chamber, 34. A spring, 39^a, may be applied to return the rod, 39, to normal position.

A swinging door, 25^b, is pivoted to the 110 side of the gear casing, 25^a, adjacent to the extension, 28^d, of the piston rod, for the purpose of enabling the pin, 19^a, which connects the piston rod with the gear, 17, to be withdrawn; when, for any purpose, it may 115 be desired to disconnect the fluid pressure operating mechanism and open and close the doors manually in the ordinary manner.

In the operation of the motor, the fireman presses his foot upon the treadle, 42, thereby 120 unseating the valve, 33, which admits fluid pressure from the supply pipe, 31, and communicating valve chamber, 34, past the grooved or reduced portion of the valve stem, 35, and through the ports, 45^a and 45, to the left hand of the operating cylinder, 25, thereby moving the piston, 28, thereof to the right, and through the connected segment gears, 17 and 17^a, imparting opening movement to the door sections, 9, 9^a. As 125 130

the piston moves forward, the valve, 53, is unseated by the shoe, 28^a, and admits fluid under pressure, from the chamber 54, to the right hand side of the piston. By reason of 5 the substantial difference of the areas of the piston subject to pressure on its opposite sides, the fluid pressure admitted on the right hand side will be sufficient only to check or cushion the stroke of the piston to 10 the right, and thus prevent slamming or shock of the doors, without preventing them from being completely opened. The unreduced portion of the shoe, 28^a, holds the valve, 53, unseated until the completion of 15 the right hand stroke. Upon the release of pressure on the treadle, 42, the valve, 33, will be seated by the fluid pressure above it, and when seated, its stem, 35, will uncover the port, 48, thereby permitting the exhaust 20 of fluid from the left hand of the cylinder to the atmosphere, through the ports, 45, 45^a, and 48. In the left hand stroke of the piston, the shoe, 28^a, holds the valve, 53, unseated, until its reduced portion comes be- 25 low the valve stem, 55, which will be near the end of the stroke, when said valve will be seated by the pressure above it. The ex- pansion of the fluid on the right hand side of the piston, and the momentum of the 30 door sections, will carry the piston to the end of its left hand stroke, when the door sections will be completely closed. The regulating valve, 51, is adjusted so as to suf- ficiently cushion the exhaust from the left 35 hand end of the cylinder to prevent the slamming of the door sections in closing.

If, by reason of failure of fluid pressure, derangement of moving parts, or for any other reason, it becomes necessary, or is de- 40 sired, to discontinue the operation of the fluid pressure mechanism, the door, 25^b, is opened, and the pin, 19^a, withdrawn and temporarily deposited on a horizontal portion of the gear casing below the door, there- 45 by disconnecting the piston rod from the gear, 17, and permitting the door sections to be manually operated by the lever, 18.

The appliance is readily applicable, in 50 connection with fireboxes of any of the ordinary constructions, and the working parts involved are comparatively few in number and of such character that they can be substantially made and are protected from liability to breakage and from damage by 55 the access of dirt. The operation of the door sections is quick, simple, and easy, and the automatic closure of the door sections effects the substantial advantage of compelling single shovel firing, the advantage of 60 which practice, in economizing fuel, perfecting combustion, and reducing firebox and flue repairs, has been universally recognized in railroad service. The facility of connection and disconnection of the operat- 65 ing mechanism and the doors is of substan-

tial advantage in providing for the opera- 70 tion of the latter under any contingencies interfering with the normal working of the former which may be presented in practice. Another important advantage is afforded in 75 the prevention of serious or fatal injury to the engineer and fireman in the event of a flue bursting or a crown sheet coming down, in which case, an ordinary swinging door would be blown open, allowing the steam and hot water to escape into the cab of the engine.

With the mechanically operated door above described, if the door sections should be open and the fireman be firing, the 80 moment he relieves pressure from the treadle the door sections will be automatically closed, thereby preventing the ingress 85 of steam and hot water to the cab, and causing them to be blown down through the grate.

I claim as my invention and desire to secure by Letters Patent:

1. The combination of a fluid pressure cylinder which is open at one of its ends, 90 a differential piston working in said cylinder, a piston rod passing through the open end of said cylinder, a gear coupled detachably to said piston rod, an operating valve controlling the supply and exhaust of fluid to and from the larger end of the piston, a valve controlling the supply of fluid to the smaller end of the piston, and means projecting into the path of and actuated by the movement of the piston, for opening said 100 last recited valve.

2. The combination of a fluid pressure cylinder, a differential piston working there- 105 in, an operating valve which, when unseated, admits fluid pressure to the larger end of the piston, and, when seated, exhausts fluid pressure therefrom, and which is continuously subject to fluid supply pres- 110 sure, means for unseating the operating valve, and means projecting into the path of and actuated by the movement of the piston, for effecting the supply of fluid to the smaller end thereof.

3. The combination of a fluid pressure cylinder, a differential piston working there- 115 in, an operating valve which, when unseated, admits fluid pressure to the larger end of the piston, and when seated, exhausts pressure therefrom, and which is continu- 120 ously subject to fluid supply pressure, means for unseating the operating valve, a valve controlling the supply of fluid to the smaller end of the piston, and a recessed shoe car- 125 ried by the rod of the piston and adapted to unseat, and hold unseated, said last recited valve during the major portion of the trav- erse of the piston in each direction.

4. The combination of a fluid pressure cylinder, a differential piston working there- 130 in, a valve chamber in the cylinder, adjoin-

ing the larger end of the piston, a fluid pressure supply pipe open continuously to the valve chamber, supply and exhaust ports leading into and out of the cylinder on the 5 larger end of the piston, a valve normally seated under supply pressure, in the valve chamber, and controlling communication between said chamber and the cylinder and between the cylinder and the exhaust port, 10 means for unseating said valve, a second pressure chamber in the cylinder, a port connecting said chamber with the supply pipe, a supply port leading into the cylinder from said second pressure chamber, a 15 valve normally seated in said pressure chamber and controlling communication between said chamber and the cylinder, and means projecting into the path and actuated by the movement of the piston, for unseating said 20 valve.

5. The combination of a fluid pressure cylinder, a differential piston working therein, an automatically seating operating valve controlling the supply and exhaust of fluid 25 to and from the larger end of the piston, means for unseating said operating valve, an automatically seating valve controlling the supply and exhaust of fluid to the smaller end of the piston, and means projecting into the path and actuated by the movement of the piston, for unseating said 30 last recited valve.

6. The combination of a fluid pressure cylinder, a differential piston working therein, an automatically seating operating valve 35 controlling the supply and exhaust of fluid to and from the larger end of the piston,

means for unseating said operating valve, an adjustable regulating valve for varying the area for exhaust from the corresponding end of the cylinder, an automatically seating valve controlling the supply of fluid to the smaller end of the piston, and means projecting into the path and actuated by the movement of the piston, for unseating 45 said last recited valve prior to the seating of the operating valve.

7. The combination of a fluid pressure cylinder, a differential piston working therein, a valve chamber in the cylinder, a fluid 50 pressure supply pipe open continuously to the valve chamber, supply and exhaust ports leading into the cylinder, a valve normally seated, under supply pressure, in the valve chamber and controlling communication between said chamber and the cylinder and between the cylinder and the exhaust port, a treadle mechanism for unseating said valve, a second valve chamber in the cylinder, a port connecting said chamber with the supply pipe, a supply port leading into the cylinder from said second valve chamber, a valve normally seated in said valve chamber and controlling said port, and a recessed shoe carried by the rod of the piston, and adapted to unseat, and hold unseated, said last recited valve during the major portion of the traverse of the piston in each direction.
